UNITED STATES PATENT OFFICE.

JAMES A. HINSON, OF CHICAGO, ILLINOIS.

DRAFT-RIGGING FOR CARS.

SPECIFICATION forming part of Letters Patent No. 704,802, dated July 15, 1902.

Application filed November 22, 1901. Serial No. 83,217. (No model.)

To all whom it may concern:

Be it known that I, JAMES A. HINSON, of Chicago, in the county of Cook and State of Illinois, have invented certain new and useful Improvements in Draft-Rigging for Car-Couplers; and I do hereby declare that the following is a full, clear, and exact description thereof, reference being had to the accompanying drawings, and to the letters of reference marked thereon, which form a part of this specification.

This invention relates to improvements in draw-bar draft-rigging for car-couplers, and refers more specifically to devices for absorbing the shock transmitted to the draw-bar through tractive usage and during the operation of coupling and also for lessening the effect of the recoil of the parts of the draft-rigging under the action of the springs placed under tension.

The invention consists in the matters hereinafter set forth, and more particularly pointed out in the appended claims.

In the drawings, Figure 1 is a side elevation of a familiar form of draft-rigging, showing my invention applied thereto. Fig. 2 is a plan view of the draft-rigging, showing the draft-sills on either side thereof. Fig. 3 is a longitudinal vertical section of the draft-rigging, taken on line 3 3 of Fig. 2. Fig. 4 is a transverse vertical section thereof, taken on line 4 4 of Fig. 3.

As shown in said drawings, A A designate the draft-sills, which are attached to the under sides of the forward ends of longitudinal floor-sills B.

C is a transverse end sill of the car-floor frame, and D the buffer-sill.

E designates the draw-bar of the coupler, located centrally between the draft-sills A and supported at its outer end below the buffer-sill by a stirrup e. To the inner end of said draw-bar is attached a yoke E². F F' designate two coiled spiral springs, one with-

in the other, which are located between the arms of said yoke and are held from vertical displacement by said arms. Said springs bear at their ends against follower-plates G, located at the forward and rearward ends of the yoke, and said follower-plates fit at their opposite ends in recesses or notches in the inner faces of draft-plates H, attached to the

draft-sills, said plates having the usual forwardly and rearwardly facing shoulders, as indicated in dotted lines in Fig. 2, which act 55 to limit the forward and rearward movements of said follower-plates. The springs F F' act in the usual manner to yieldingly resist the end thrust of the draw-bar with respect to the draft-sills in either direction and to thereby cushion the blows due to such movements of the draw-bar in tractive usage and during coupling operations.

The improvements constituting my invention consist in applying to the draft-rigging 65 of the general type described or other equivalent type a supplemental spring or springs which act in a direction transverse to the direction of compression of the draw-bar spring or springs, of which latter there may be one 70 or two, and interposing between said draw-bar and supplemental spring or springs friction-producing means which are brought into use subsequently to the preliminary action of the draw-bar and supplemental springs. In 75 other words, the draw-bar and supplemental springs are placed under preliminary stress at approximately the same instant at the time the draw-bar begins to move in either direction, and subsequently in the continued movement of the draw-bar the friction-producing means are brought into action and act, in conjunction with said springs, to augment or increase the resistance to the movement of said draw-bar. Preliminary strains and those 85 which are comparatively moderate in their force and effect which occur in tractive use are opposed by the resistance of the draw-bar and supplemental springs in their preliminary stress, the friction-producing means be- 90 ing at this time inactive, while tractive and buffing strains which exceed the capacity of such preliminary action of the draw-bar and supplemental springs are resisted by the combined effect of said springs and the friction- 95 producing means.

The supplemental spring or springs may be of any preferred or convenient form, and as herein shown consists of a U-shaped leaf-spring I, generally like that shown in my prior 100 United States patent, No. 684,246, granted October 8, 1901. Said spring is located between the draft-sills with the free ends of its arms extending above and below the draw-bar, and is

attached at the center of its loop to the draft-sills by means of a clip I', attached to the said draft-sills in the manner shown in Fig. 2. The friction-producing means referred to are interposed between the ends of said springs and the draw-bar, and consist of friction-blocks J, carried by and movable with the draw-bar yoke and having laterally-facing bearing-faces, and other friction-blocks K, having bearing-faces complementary to those of the blocks J and held against said blocks J by means of the arms of the spring I. Preferably the bearing-surfaces of said blocks consist of alternately-reversed inclined faces, as clearly shown in Fig. 3, whereby when the blocks J are moved relatively to the blocks K the inclined surfaces of the blocks act to spread the arms of the spring I, and thereby increase the tension of said spring. The blocks J are recessed on their inner faces to fit over the draw-bar yoke in the manner shown in Fig. 3, whereby said blocks are held from longitudinal and transverse displacement, and the blocks K are held in place by the tension of the arms of the spring I. Said blocks K are strengthened by longitudinal ribs K', formed on their outer faces.

The operative connections between the arms of the spring I and the outer friction-blocks K, whereby said spring I is placed under preliminary stress or tension in the first part of the movement of the draw-bar in either direction and prior to the operation of the friction-producing means, consist of rollers L, mounted in bearings formed on the outer faces of said friction-blocks, and bearing-castings I², attached to the ends of the spring-arms and provided with inwardly-facing reversely-inclined bearing-surfaces i i', adapted to engage said rollers L, said inclined surfaces i i' being so disposed as to form central depressions between the same, in which the rollers rest when in their normal or inactive positions. At the forward and rearward ends of said inclined surfaces i i' are formed vertical stop-shoulders i² i³, as shown in Fig. 3, which act to limit the longitudinal movement of the rollers and the friction-blocks K, which carry the same, in both directions. Said bearing-casting L is provided at its side margins with vertical flanges l, which overlap the ribs K' of the outer bearing-blocks K and prevent relative lateral movement of said parts. With this construction both sets of friction-blocks move with the draw-bar in the first part of the movement of the latter and until the rollers strike one pair of the stop-shoulders i² i³, depending upon the direction of movement of the draw-bar, this movement being permitted by reason of the limited travel of the rollers with respect to said bearing-castings of the supplemental spring. When said rollers strike said stop-shoulders, the movement of the outer friction-blocks K is arrested, and if the movement of the draw-bar and inner friction-blocks be continued the friction-producing means will be brought into operation.

The operation of the device described is as follows: When a relatively light strain is transmitted to the draw-bar, such as would occur in traction due to slight undulations of the road-bed or in gently starting or stopping the train, the draw-bar is moved inwardly or outwardly, as the case may be, thereby placing the springs F F' under compression, and by reason of the limited relative movement of the outer friction-blocks K and rollers L with respect to the bearing-castings I² said rollers are at the same time moved outwardly or inwardly, as the case may be, over one pair of the inclined bearing-surfaces i i' and cause said spring I to be placed under tension and to thereby act, in conjunction with the draw-bar spring, to resist or counteract such movement of the draw-bar. The action of the draw-bar and supplemental springs continues in this manner until the movement of the draw-bar is sufficient to bring the rollers L into contact with either of the stop-shoulders i² or i³. When this occurs, the movement of the outer friction-blocks K is arrested, and should the force transmitted to the draw-bar be sufficiently great to continue the movement of said draw-bar and of the friction-blocks J, which latter move at all times with the draw-bar, said friction-blocks J will move upon or relatively to the friction-blocks K, thereby producing frictional resistance between said blocks, which is added to the resistance of the springs and greatly increases the resistance to the movement of the draw-bar. The parts are of course in practice so proportioned that the combined spring and friction resistance is sufficient to absorb or counteract the practical maximum strains which may be transmitted to the draw-bar. In case the friction-blocks be provided with reversely-inclined faces, as shown, and which is a preferred construction, the movement of the friction-blocks J on the blocks K causes further tension to be placed on the supplemental spring I, thereby augmenting the resistance of said spring and also augmenting the frictional resistance between the blocks J and K. In practice the travel of the rollers L from their central positions to the stop-shoulders i² i³ (where the draw-bar has a total movement of from two to two and one-quarter inches in either direction) will be from three-quarters of an inch to one inch and the movement of the friction-blocks relatively to each other subsequently to the preliminary stress of the springs from one and one-quarter to one and one-half inches. As before stated, the draw-bar and supplemental springs are in practice so proportioned as to absorb the ordinary tractive and the lesser buffer strains without bringing the friction-producing means—to wit, the friction-blocks J and K—into action, and resistance due to the action of the friction-blocks, acting in conjunction with the spring resistance of the draw-bar and supplemental springs, is sufficient to absorb the

strains and shocks transmitted to the draw-bar in emergency tractive uses and in coupling.

It is to be understood that the form of the 5 spring may be varied, and, if desired, the said spring and the friction-producing means may be applied to one side of the draw-bar only. Moreover, it is obvious that the same results will be produced if the rollers be mounted on 10 the springs and coöperate with inclined surfaces on the outer friction-blocks K. It is further obvious that many other changes may be made in the details of the construction without departing from the spirit of my invention, and I do not wish to be limited there- 15 to except as hereinafter made the subject of specific claims.

I claim as my invention—

1. A draft-rigging for cars, comprising a 20 draw-bar, a draw-bar spring, a supplemental spring, means for placing said supplemental spring under stress in a direction transverse to the direction of compression of the draw-bar spring through longitudinal movement of the draw-bar, friction-producing means interposed between the draw-bar and said supplemental spring, and means acting to bring said friction-producing means into operation sub- 25 sequently to the preliminary action of said 30 supplemental spring and draw-bar spring.

2. A draft-rigging for cars, comprising a draw-bar, a draw-bar spring, a friction-block carried by the draw-bar, a complementary friction-block, a supplemental spring for holding 35 said blocks pressed one against the other, and means acting to first place said supplemental and draw-bar springs under preliminary stress and to thereafter cause the draw-bar friction-block to move relatively to the other friction-block in the continued movement of the draw-bar.

3. A draft-rigging for cars, comprising a draw-bar, a draw-bar spring, a friction-block carried by the draw-bar, having reversely-in- 45 clined bearing-surfaces, a complementary friction-block, a supplemental spring for holding said blocks pressed one against the other, and means acting to first place said draw-bar and supplemental springs under preliminary 50 stress and to thereafter cause the draw-bar friction-block to move relatively to the other friction-block in the continued movement of the draw-bar, the friction-blocks acting in such continued movement of the draw-bar to 55 place the supplemental spring under stress.

4. A draft-rigging for cars, comprising a draw-bar, a draw-bar spring, a supplemental spring which acts transversely to the direction of compression of the draw-bar spring, a 60 friction-block carried by the draw-bar, a complementary friction-block which is pressed against said draw-bar friction-block by said supplemental spring, both of said friction-blocks being movable with the draw-bar and 65 relatively to the supplemental spring in the preliminary stress of the supplemental and draw-bar springs, coacting parts carried by

said supplemental spring and one of the friction-blocks acting to place said spring under tension in the initial movement of the draw- 70 bar, and stops acting to limit the movement of the last-mentioned friction-block subse- 75 quently to the preliminary stress of the said supplemental and draw-bar springs and to cause the draw-bar friction-block to move relatively to the complementary friction-block in the continued movement of the draw-bar.

5. A draft-rigging for cars comprising a draw-bar, a draw-bar spring, a supplemental spring which acts transversely to the direction 80 of compression of the draw-bar spring, a friction-block carried by the draw-bar, a complementary friction-block which is pressed against said draw-bar friction-block by said supplemental spring, both of said friction-blocks be- 85 ing movable with the draw-bar and relatively to the supplemental spring in the preliminary stress of the supplemental and draw-bar springs, coacting parts carried by said supplemental spring and one of the friction-blocks, 90 consisting of a roller on one part and a reversely-inclined surface on the other part act- 95 ing to place said supplemental spring under tension in the initial movement of the draw-bar, and stops acting to limit the movement of the last-mentioned friction-block subse- 100 quently to the preliminary stress of the sup- 105 plemental and draw-bar springs, whereby the draw-bar friction-block is caused to move relatively to its complementary friction-block in the continued movement of the draw-bar.

6. A draft-rigging for cars comprising a draw-bar, a draw-bar spring, a supplemental spring which acts transverse to the direc- 110 tion of compression of the draw-bar spring, a bearing-block carried by said supplemental spring, a friction-block carried by the draw-bar, a complementary friction-block which is held pressed against said draw-bar friction- 115 block by said supplemental spring, one of said parts, to wit, the bearing-block or said complementary friction-block being provided with a roller and the other part with reversely-in- clined coacting surfaces, and stops on said bearing-block for limiting the movement of the roller and the friction-block carrying the same relatively to said supplemental spring.

7. A draft-rigging for cars, comprising a draw-bar, a draw-bar spring, supplemental springs on each side of the draw-bar which 120 act transversely to the direction of compres- 125 sion of the draw-bar spring, friction-blocks one on each side of and carried by the draw-bar, complementary friction-blocks which are pressed against said draw-bar friction-blocks by said supplemental springs, both sets of said friction-blocks being movable with the draw-bar and relatively to the supplemental springs in the preliminary stress of the supplemental and draw-bar springs, coacting 130 parts carried by said supplemental springs and one set of the friction-blocks acting to strain said supplemental springs in the initial movement of the draw-bar, and stops act-

ing to limit the movement of the last-mentioned friction-blocks subsequently to the preliminary stress of the supplemental and draw-bar springs, whereby the draw-bar friction-blocks are caused to move relatively to their complemental friction-blocks in the continued movement of the draw-bar.

5 In testimony that I claim the foregoing as

my invention I affix my signature, in presence of two witnesses, this 23d day of October, A. D. 1901.

JAMES A. HINSON.
